UNITED STATES PATENT OFFICE.

ALEXANDER HUNTER, OF MUSKEGON, MICHIGAN.

CAN-OPENER.

SPECIFICATION forming part of Letters Patent No. 417,032, dated December 10, 1889.

Application filed July 20, 1889. Serial No. 318,129. (No model.)

To all whom it may concern:

Be it known that I, ALEXANDER HUNTER, a citizen of the United States, residing at Muskegon, in the county of Muskegon and State 5 of Michigan, have invented certain new and useful Improvements in Can-Openers; and I do hereby declare the following to be a full, clear, and exact description of the invention, such as will enable others skilled in the art 10 to which it appertains to make and use the same.

This invention relates to an improvement in can-openers or devices for removing the ends of tin or other cans and similar receptacles, the object of the invention being to provide a simple, cheap, and practicable device 15 so constructed that circular or square cans may be opened thereby with equal facility.

The invention consists, essentially, in the 20 combination, with a handle, of specially-constructed cutters, one of which is designed for the purpose of opening a head or end of a square can, while the other is specially devised for the particular purpose of opening a 25 round can. These two knives or cutters are placed on opposite sides of a central projection on the head of the handle.

The invention further consists in certain 30 peculiarities in the construction, arrangement, and combination of the several parts of the device, substantially as will be herein-after more fully described, and then particularly pointed out in the appended claims.

In the accompanying drawings, illustrating 35 my invention, Figure 1 is a front elevation of my improved can-opener with all the parts in normal position. Fig. 2 is a side or edge view of the same, showing the cutter which is adapted for opening square cans. Fig. 3 is a 40 similar side or edge view showing the cutter which is adapted for opening circular cans. Fig. 4 is a plan view of the device complete.

Similar letters of reference designate corresponding parts throughout all the different 45 figures.

A denotes the handle of my improved can-opener. It may be made in any desirable and convenient form, that form indicated in the drawings being only an example of one 50 way in which it is preferably constructed. Near the upper end of the handle, and pref-

erably cast integral therewith, is a bar or T-shaped head a, which is properly formed to permit the easy attachment thereto of the cutting-blades. Extending beyond the head 55 a is a projection B, which likewise forms a part of the same casting as the head and handle. This projection B is flattened to provide two flat faces, as shown in Fig. 3, said projection being preferably somewhat in the 60 form of an enlarged screw-driver. Said projection is used as the fulcrum for the device when the straight knife is in operation cutting around the edge of a square can. In Figs. 2, 3, and 4 the broad surface or flat face 65 of this projection is clearly shown.

D denotes the straight cutter used in opening square cans. This cutter is located, as shown in Fig. 1, at the right of the projection B, the lower end of the cutter being firmly 70 secured by the rivet d to one end of the head a, which is properly grooved, as shown in dotted lines, to receive the end of the cutter and permit it to be properly connected thereto, said end of the cutter being also slightly 75 tapered to correspond with the shape and size of the groove into which it fits. This groove, in connection with the tapered end of the cutter and the rivet, serves to form a lock whereby the cutter is securely held in place, so as 80 to be immovable. The end of the head at this point is slightly rounded, as shown in Fig. 2.

C represents the curved cutter, which is 85 adapted for opening circular cans. This is located alongside of the projection B at the left side thereof, as shown in Fig. 1, said cutter being on the side of the projection opposite to where the straight cutter is located. The lower end of the curved cutter is connected to the end of the head a in a similar 90 manner to that in which the straight cutter is connected to the opposite end of said head. The rivet c serves to hold the curved cutter firmly in place within the groove which is 95 adapted to receive it. This cutter is curved laterally from end to end. (See Fig. 3.) Its curvature may be greater or less, as desired. It is usually but a slight curvature, the object of the curved form being to more readily 100 adapt it to cut around a circular can. The head at the point where the lower end of the

cutter C is attached thereto is provided with a projection a' , integral with the casting of the head, which projection is used as a guide on the outside of the circular can when the 5 curved cutter is being used.

Both the cutters C and D are chamfered on both sides of the inner faces, so as to form a good cutting-edge. The edges of said cutters are curved, and the cutters terminate in 10 points. This is the preferable form of the cutters.

The operation or use of this device which I have just described in opening cans is as follows: When the device is to be used with 15 a circular can, the curved knife will be inserted as near the edge of the can as possible, using the projection a' as a guide on the outside of the can. The user of the device will then propel the cutter along, using the round- 20 ed part of the head as a fulcrum. When square cans are to be cut, the operator will insert the straight knife into the tin, using the central projection B as a fulcrum in this case. By the use of this straight knife and the flat- 25 tened projection square cans can be cut as easily around the four corners thereof as they can along the body or side of the can. This is a great improvement over other devices

now in use. My improved can-opener therefore combines in a simple, cheap, and practical device means for opening with equal facility a round or a square can, and the device operates successfully in both instances. 30

Having thus described my invention, what I claim as new, and desire to secure by Letters 35 Patent, is—

1. In a can-opener, the combination, with the handle having a head and the central projection serving as a fulcrum, of the straight knife on one side of said projection and the 40 lateral curved knife on the other side thereof, substantially as described.

2. In a can-opener, the combination of the handle A, having a head a, one end of which is furnished with the guide-flange a' , the flattened projection B, integral with the head, the straight knife D, secured to one end of the head, and the laterally-curved knife secured to the opposite end of the head, substantially as described. 45

In testimony whereof I affix my signature in presence of two witnesses.

ALEXANDER HUNTER.
